UNITED STATES PATENT OFFICE.

ELMER J. BREWSTER AND JOHN MURRIN, OF CHICAGO, ILLINOIS.

MECHANISM FOR RECLAIMING DEFECTIVE LOCOMOTIVE AND STEAM CYLINDERS.

1,209,112.

Specification of Letters Patent. Patented Dec. 19, 1916.

Application filed April 23, 1915. Serial No. 23,313.

To all whom it may concern:

Be it known that we, ELMER J. BREWSTER, residing at Chicago, in the county of Cook and State of Illinois, and JOHN MURRIN, residing at Chicago, in the same county and State, both citizens of the United States, have invented a certain new and useful Improvement in Mechanism for Reclaiming Defective Locomotive and Steam Cylinders, of which the following is a specification.

As anyone familiar with railroad locomotives well knows, the steam cylinders and valve cylinders supplying steam thereto are ordinarily contained in very heavy, cumbersome and expensive castings which if broken are practically non-weldable, and that steam is supplied to the cylinder proper through the valve cylinder or other device in a passageway formed in the casting itself which causes unequal expansion and contraction of the metal of the casting with the result that in the past quite a large percentage of devices of this kind were broken in or through the steam supply pipe because of this unequal expansion. The result of these facts has heretofore been that it was necessary to throw away the entire casting long before the cylinder device was worn out and as this meant the throwing away of \$500, *i. e.*, the value of such castings, it has been a very serious matter with railroads and other concerns using locomotives and other engines having cast cylinders of this class.

The object of this invention is to provide means for repairing these cast cylinders when they do break in the steam supply pipe and thus render them usable through the remainder of their normal lives without decreasing the efficiency of the device.

The invention consists more particularly in mechanism for so repairing locomotive cylinders.

It further consists in the features and details which will be hereafter more fully described in the specification and claimed.

Referring to the drawings in which similar numerals indicate the same parts throughout the several views, Figure 1 is a side view one-half in central section of a locomotive steam cylinder and its valve cylinder. Fig. 2 is a sectional end view looking at the parts as shown in Fig. 1 from the right. Fig. 3 is a side view partially in

section of a supplementary cylinder lining applied to the valve cylinder carrying out this invention. Fig. 4 is a side view of a supplemental or saddle casting applied to the valve cylinder in carrying out this invention. Fig. 5 is a bottom view of the casting shown in Fig. 4.

The device is, of course, applicable to any type of engine cylinder single, compound or triple expansion and to any form of engine whether it is a railroad locomotive or not. Simply for purposes of illustration, the device is shown applied to the single cylinder 10 of a locomotive controlled by a valve cylinder 12, the two being contained within a large general casting 14 which itself contains the steam passageway 16 leading from the locomotive boiler 18 to the valve cylinder 12. As in all locomotives of this type, a valve piston device forming no part of this invention and therefore not shown, is movable within the valve cylinder 12 to control admission of steam from the passage 16 through ports 20 and passageway 22 into the main engine cylinder 10 in which the power piston reciprocates in the ordinary manner. The problem solved by this invention is to repair this general casting and the parts thus far described contained therein when a break occurs due to unequal expansion and contraction of the metal in the passageway 16 so that said passageway no longer will conduct steam from the locomotive boiler to valve cylinder 12. When such a break occurs in passageway 16 an opening is made in the top of the valve cylinder of such size as to receive the saddle casting 22 which is provided with a central steam passageway 24 ending in a flange 26 and provided on its sides with flanged members 28 and 30 adapted to fit over and generally conform to the exterior configuration of the casting 14. Through the flanges just described are suitable holes 32, 34 for the studs to secure this saddle casting in place in the general position just shown in Fig. 2. All this can be done without removing the cylinder from the engine.

The central body portion of saddle casting 22 is made initially of greater depth than the thickness of the walls of cylinder 12 so that when the saddle casting is first placed in position it extends substantially into the cylinder 12. No attempt is made to make the saddle casting as thus far de-

scribed engage the main casting 14 in a steam tight fit. In other words, it is applied in loose fit and rigidly secured in position. When the saddle casting has been 5 thus applied the cylinder 12 is rebored sufficiently so that it will take the supplemental cylinder or sleeve 36, shown in Fig. 3, whose internal diameter is that of the original valve cylinder. In thus boring out the valve 10 cylinder 12 the lower portion of the saddle casting 22 is, of course, cut away as shown in Fig. 2. When this operation has been completed the supplemental cylinder 36 is put in place with its previously prepared 15 steam port 38 registering with passageway 24 in the saddle casting 22 and its ports 40 registering with the ports 20 heretofore referred to. As the central body portion of this cylinder 36 is otherwise unperforated, 20 it effectively closes passageway 16 through which the steam originally entered the valve cylinder and thus transfers the steam supply port from passageway 16 to passageway 24. The passageway 16 is now preferably filled 25 with asbestos not shown in the drawings and the plate 42 secured over the end of the passageway 16 by any suitable means as for instance the screws 44.

When the casting 14 has been thus re- 30 paired, any suitable pipe device as 46 is attached to the saddle casting and connected to the boiler 18 and secured in place by any suitable means as for instance bolts passing through suitable holes 48 in the flange 26 35 and the saddle casting and flange 50 on the pipe 46. The valve mechanism not shown is then replaced in the cylinder 36—12 and the device is ready for operation just as though no break had occurred in pipe 16.

40 Many changes may be made in details of applying the various parts named to the valve cylinder and in the form of the valve cylinder to which the parts are applied

without departing from this invention, as set forth in the claims.

While the device has been shown as applied to an engine having a cylindrical valve chamber, it may obviously be applied to engines having other shapes of valve devices without departing from this invention.

Having thus described our invention, what we claim as new and desire to secure by Letters Patent, is:—

1. In an engine, the combination of a casting including a valve cylinder and having a passage therein leading to the cylinder, a saddle casting having a passage therethrough inserted in an opening in the cylinder remote from the passage leading to the cylinder, means for securing said saddle casting to the cylinder, and a cylindrical lining inserted in the cylinder to close the first named passage and forming a steam tight joint between same and the cylinder and between same and the saddle casting, said lining having an opening therein registering with the passage in the saddle casting.

2. In an engine, the combination of a valve cylinder, a saddle casting having a passage therethrough inserted in an opening in the cylinder, means for securing said saddle casting in position to the cylinder, and a cylindrical lining inserted in the cylinder and having an opening therein registering with the passage in the saddle casting, said lining forming a steam tight joint between same and the cylinder and between same and the saddle casting.

In witness whereof, we have hereunto subscribed our names in the presence of two witnesses.

ELMER J. BREWSTER.
JOHN MURRIN.
